To all whom it may concern:

Be it known that I, Lawrence Blazey, a citizen of the United States, residing at Cleveland, in the county of Cuyahoga and State of Ohio, have invented a new, original, and ornamental Design for a Radio Cabinet, of which the following is a specification, reference being had to the accompanying drawing, forming part thereof.

The figure is a perspective view of a radio cabinet, showing my new design.

I claim:

The ornamental design for a radio cabinet,
as shown,

LAWRENCE BLAZEY.
